UNITED STATES PATENT OFFICE

MAX BREIDENBACH, OF MAINZ, GERMANY

GAME

Application filed May 20, 1929, Serial No. 364,547, and in Germany October 1, 1928.

This invention relates to an apparatus for use in a game adapted to be played between two players.

The object of the invention is to provide an apparatus for use in a game which will bring into use almost all of the muscles of the body.

A further object is the provision of an apparatus relatively inexpensive which has few parts and which can be used to give a high competitive game between two people.

A still further object is the provision of a sport ball secured to an elastic rope midway between two handles to give an apparatus for a new game.

15 The invention is illustrated in the accompanying drawing, in which Figures 1 and 2 are perspectives of the entire device and of the joint between the elastic and handle respectively, the latter on an enlarged scale.

20 As illustrated, the apparatus comprises an elastic cord or rope *a* which may be of any convenient length but it has been found by experiment that a length of approximately three meters will allow the best results to be had. Secured to each end of the rope are handles *b* while firmly attached to the rope and midway between the two handles is a sport ball *c*.

25 This ball, which is of the usual inflated type, is about the size of a volley ball and is made of a soft light material which will cause no injury to the players even though struck in the face with it. Secured to the ball in a manner that renders it part of the cover is a strap *d* by means of which the ball is fastened to the rope *a* at *e*. The strap is about equal in length to the diameter of the ball and is securely fastened to the rope so that there is no sliding movement of the strap on the rope. However, the length of the strap allows a certain freedom of movement to be given the ball.

30 The handles *b* are rotatably attached to the cord so that no matter how many turns the cord or ball takes, said cord will not become

twisted. Fastened to the handles are wires *k* which are swivelled at *g* to rings *h*, the latter being fastened to the ropes *a*, as by turning the ends over as at *i* and securing said ends in any suitable manner.

35 The game, which is a sort of fencing ball game, is played by two players facing each other across a neutral or dividing line. The players take a position of from one and one-half to two meters from the line, holding the handles in one hand, the ball suspended over the line. The ball is brought into play by rapid movement of the players' bodies and arms advancing and retreating to and from the line which must not be overstepped by a 40 player. The object of the game is to try to bring the sport ball into contact with an opponent's body, each contact counting a point against the man who is hit. The game, which is exceedingly fast, is played alternately with each hand and brings into play most of the 45 muscles of the body.

50 Such a game as above described could be played outdoors or indoors and provides fast action for the players, besides giving the 55 body the so necessary stretching and bending exercises which come through trying to dodge the ball and also to land it against an opponent's body.

55 What is claimed to be new is:

1. An apparatus for a ball game comprising a single elastic support, a ball carried by the support, and handles at each end of the support whereby the elastic is extended or allowed to retract by a force at the handles.

2. An apparatus for a ball game comprising a single elastic support, a ball carried midway of the support, and handles at each end of the support to allow a force to be applied for stretching the elastic support.

3. An apparatus for a ball game comprising a single elastic cord, a ball carried midway of the cord, and handles at each end of said cord to allow a force to be applied for stretching the cord.

4. An apparatus for a ball game comprising a single elastic cord, a ball, a strap secured to the ball, said strap being fastened to the cord, and handles at each end of the cord whereby movement of the handles im-
5 parts motion to the ball.

5. An apparatus for a ball game comprising a single elastic cord, a ball, a strap secured to the ball, said strap being fastened to the midpoint of the cord, and handles at each 10 end of the cord whereby movement of the handles imparts motion to the ball.

In testimony whereof I affix my signature.
MAX BREIDENBACH. [L. S.]
